UNITED STATES PATENT OFFICE.

JONATHAN C. MELOON, OF PROVIDENCE, RHODE ISLAND, ASSIGNOR TO GENERAL FIRE EXTINGUISHER COMPANY, OF PROVIDENCE, RHODE ISLAND, A CORPORATION OF DELAWARE.

VALVE.

Application filed September 24, 1925. Serial No. 58,301.

This invention relates to improvements in valves. More particularly it relates to anti-columning improvements in differential dry pipe valves in which a liquid, usually water, under pressure, is held in check by a less pressure of air thereupon, as in sprinkler systems. Valves of this character are ordinarily provided with a movable valve member having one side (known as the air face or air clapper) of considerably greater working area than the other, (known as the water face or water clapper) thus permitting a relatively small pressure per square inch on the side having the large working area to hold the valve member on its seat within the casing against a greater pressure acting on the side having the smaller working area. In sprinkler systems for buildings the sprinkler heads and distribution pipes are connected to the side of the valve having the large working area, the air in the pipes acting on said area, and the water supply is connected to the side having the smaller working area, exerting a pressure on that area. When a sprinkler head opens, the air in the distribution pipes rushes out, thus lowering the pressure in the valve and permitting the opening thereof under pressure of the water. The sudden rush of water into the distributing pipes of the system containing air which acts as an elastic cushion, together with the slow rate of escape through the open head or heads, causes a surge back to the valve which may result in the closing of the valve. At any such time the weight of the column of water in the riser on the sprinkler side of the valve tends to hold the valve closed; and this tendency is magnified by the differential character of the valve, so that the pressure from the supply main may be insufficient to reopen the same valve, producing a condition known as "columning" of the valve. Under these circumstances the sprinkler system would be locked in inoperative condition. The preventative is to provide an opening which becomes effective to permit equality of pressures on the dry pipe valve, by permitting free passage of liquid by either clapper to the other, after it has once opened, and this general principle has long been known.

It is an object of the present invention to provide an improved means within valves

of this class which will prevent columning after initial opening of the valve. In particular the invention provides an anti-columning device which is positively operated by the high pressure of the supply; one which is an auxiliary valve that while waiting ready for operation is held tightly closed by the air pressure acting through the differential valve; one whose leakage, if any, does not diminish the air pressure; one which is self adjusting so as to become closed in synchronism with the closing of the main valve; and one whose opening, when it occurs, is so disruptive that its closure cannot be re-established except by the intervention of human intelligence.

These objects are attained by providing the ordinary differential dry pipe valve with a passage leading from the supply inlet directly to the intermediate chamber of the valve. This chamber is ordinarily in direct communication with the atmosphere and has a drain for leaking water. The said passage has the anti-columning valve, normally held closed by the pressure of the main valve member, but released when said member opens. Whenever such a release occurs the main water supply pressure forces the anti-columning valve open, thrusting it out of the passage, and a spring pulls it to one side where it falls in a lateral pocket, so that both gravity and the said spring prevent its accidental return to its seat. Thus, simultaneously with the opening of the main valve, a permanent passage is opened from the supply to the intermediate chamber, opening it to the pressure of the supply and preventing the restoration of the differential characteristic of the valve, in case the main valve should close, for the supply pressure can thereafter act upon a surface as large as that on which the water column may rest. This converts the dry pipe valve to a mere one way valve, which can always open when there is upward pressure enough to lift its mere weight.

One manner of applying the invention is illustrated in the accompanying drawings, it being understood, however, that the same may be applied in various ways. It is intended that the patent shall cover by suitable expression in the appended claims whatever features of patentable novelty exist in the invention disclosed.

In the drawings:

Figure 1 is an elevation, in medial section, of a valve embodying the invention;

Figure 2 is an elevation in section through 5 the auxiliary valve mechanism;

Figure 3 is a plan in section on the line 3—3 of Figure 1 showing the auxiliary valve in closed position; and

Figure 4 is a similar view showing the 10 auxiliary valve in open position.

Referring to the drawings, the numeral 10 indicates generally the casing of a differential valve, having a supply inlet 12 at one end and an outlet 14 to the distribution riser 15 of a sprinkler system at the other end. The inlet passage extends a substantial distance within the casing and has on its inner end a valve seat 16 adapted to be engaged by the under side of a valve disc 18 pivotally 20 mounted as at 20 within the main casing. A gasket 22 on the under side of the valve disc engages the valve seat 16, to make a watertight closure when the valve disc 18 is in closed position. Above the valve disc is a 25 chamber 24 having in the margin of its bottom a valve seat 30 of considerably greater diameter than the seat 16; and against this the rubber edge 32 of the disc seats so that the fluid in the chamber 24 exerts its pressure 30 upon the entire surface area of the valve disc 18, permitting a relatively small pressure per square inch on the upper side to retain the disc upon its seat against the greater pressure per square inch of the water applied 35 to the restricted area on the under side. Between the seats of these two valves is the intermediate chamber 28 which while the valves are closed is open to atmosphere through the customary drip pipe 26 which 40 may be equipped with any suitable valve, for permitting a small flow of water to escape, and for closing at inception of the large flow which occurs when the main valve opens, many devices for which are known.

Extending from the supply inlet 12 to the intermediate chamber 28 is by-passage 34, and this passage has in its upper end an auxiliary valve casing 36 the upper end of which forms a valve seat 38 for an auxiliary 45 valve 40. A gasket 42 on the under side of the valve 40 presses on the valve seat 38. The main valve disc 18 holds this closed. It exerts its pressure upon the spring top 50 of this auxiliary valve 40, which has a two 55 ply dome of convex discs 44 of resilient material, such as brass. These are adapted to yield stiffly, sufficiently to permit of the main valve disc 18 engaging them before it is itself seated, after which it depresses them 60 until it comes to its seat 16; and these discs are stiff enough to hold the valve 40 thereafter closed against the water supply pressure. The intermediate chamber 28 is conveniently made in the form of a circular 65 groove, in which there extends radially from

the auxiliary valve casing 36 a fixed bracket 52 in which there slides radially a rod 50 whose inner end is attached by yoke 48 to the valve 40. Beyond the upstanding portion 52^a of the fixed bracket 52, through 70 which the slidable radial rod passes, there is a coiled spring strung on the rod, and outside of that is a washer 54 retained thereon by a cotter pin or the like. The spring 56 exerts pressure tending to thrust the rod 50 75 outward, carrying the valve 40 to the removed position indicated by dotted lines in Figure 2 of the drawings; and this movement is normally restrained, when the valve is closed, by the latching engagement of the 80 central part of the valve 40 within its seat 38. When the said valve is unseated by the water pressure, simultaneously with the opening of the main valve, it is pulled away by rod 50. Thereafter, if the valve disc 18 85 should close, water in the intermediate chamber 28 would be of the same pressure as in the supply which, acting upon the entire area of the valve disc 18, would prevent permanent closure by a water column. 90

When the dry pipe valve is set ready for action, the full pressure of water supply tends to open the by-passage to intermediate chamber, and this is normally so great that no possible sticking of the valve 40 can withstand such an opening pressure whenever this valve is free to open. But while thus waiting the valve is held closed by the superiority of total air pressure over total water pressure in the main valve and by- 95 passage and thus is held securely closed and very tight against leakage, by a force which disappears whenever the main valve actually opens. The attainment of this tightness would be a difficult matter and a rare occurrence but for the provision of the spring head 44, because of the practical difficulties in the way of making two absolutely rigid valves seat at the same instant, such as the valve seat and valves 16, 22, 40, 38. But by 100 making the shell fractions 44 concave, and sufficiently deep to extend, as regards their position of possible working travel, through the range of variations which may arise in the relations of the actual valve seats 38 and 115 16, and through the variation possible commercially in the thickness of the valve 40, a construction results in which the valve 40 becomes tightly seated whenever the valve disc 18 is seated at 22 on 16. The dome 120 spring 44 is stable against overturning when vertically compressed and by being made in two or more ply of metal is sufficiently flexible as well as sufficiently stiff to serve the purposes of the apparatus. Any leakage 125 which may occur notwithstanding the provisions does no harm to the system, for it is not a leakage of stored air but rather of supply water into the intermediate chamber from which a drain is already provided. 130

When the dry pipe valve works, the valve 40 is thrust violently open, and if it were left loose and free the chance is very small indeed that it would ever fall in position to close the opening 34, and be held down thereon, if the clapper 18 should subsequently be swung shut. But conceivably it might fall so as to overlie the edge of the valve casing 36, in which case it would constitute a barrier preventing the closure of the valve 18 and thus would act as a mechanical obstacle or latch preventing water-columning. But by so doing the parts might be injured in some way and it is therefore considered better practice, and the invention provides, for the complete removal with certainty of the valve 40 from its casing 36, thus permitting the valve 18 to close and open again as many times as surges may move it, while leaving the valve 40 in position to be reset by the inspector. It will be understood that the valve body 10 has a suitable hand hole for observation of the interior and for manipulation of the parts, which may be assumed to be in the portion of the valve not shown in Figure 1. When the valve is to be reset, it need only be placed in the position illustrated in Figure 2, whereupon its slight engagement in the interior of the valve casing 36 will latch it against pull of the spring 56. And whenever it is open the pull of this spring will hold it in the trough of the chamber 28 where it cannot be in the path of the clapper 18 of the main valve.

What I claim as my invention is:

1. The combination with a supply system valve casing having a waterway therethrough and an intermediate chamber, of a closure seating across said waterway and cutting off said chamber from the system; a by-passage from the system side of said closure to the chamber; a valve for the by-passage adapted to be opened by the system pressure when the closure is opened and held closed by the closure when the latter is normally closed; and means operative upon the opening of said valve to withdraw said valve out of the path of movement of said closure whereby the said by-passage remains open notwithstanding subsequent abnormal closing of the closure.

2. The combination with a differential valve having an intermediate chamber, of a by-passage from one side of the valve to said chamber; an auxiliary valve for the by-passage held closed by the main valve when the latter is seated, and adapted to be opened by the pressure in said by-passage when the main valve is unseated; and means operative upon the opening of said auxiliary valve to withdraw it to a position beside its seat and out of the path of movement of the main valve whereby the said by-passage remains open notwithstanding subsequent reseating of the main valve.

3. The combination with a differential dry pipe valve having an intermediate chamber, of a by-passage from the inlet side of the valve to the intermediate chamber; an auxiliary valve closing the by-passage when the main valve is closed, held closed by the main valve when the latter is closed, and adapted to be opened by the supply pressure when the main valve is opened; there being means adapted to move said auxiliary valve after its initial opening laterally from its seat and out of the path of movement of the main valve, thereby to prevent its being reseated upon the subsequent closure of the main valve.

4. The combination with a differential dry pipe valve having an intermediate chamber, of a by-passage from the inlet side of the valve to the intermediate chamber; an auxiliary valve closing the by-passage when the main valve is closed, held closed by the main valve when the latter is closed, and adapted to remain open after the latter is opened notwithstanding subsequent closure of the latter; there being a compression spring intervening between the two said valves when closed, having travel enough to cause their engagement notwithstanding variations in relative positions of valve seats, and having strength enough to resist opening by the supply pressure; and means operative upon the opening of the auxiliary valve to move said compression spring out of the path of movement of said main valve thereby to prevent the latter from reseating the auxiliary valve.

5. The combination with a differential dry pipe valve having an intermediate chamber, of a by-passage from the inlet side of the valve to the intermediate chamber; an auxiliary valve closing the by-passage when the main valve is closed, held closed by the main valve when the latter is closed, and adapted to remain open after the latter is opened notwithstanding subsequent closure of the latter; there being a dome spring intervening between the two said valves when closed, and means operative upon the opening of said auxiliary valve to withdraw said spring out of the path of movement of said main valve.

6. The combination with a differential dry pipe valve having an intermediate chamber, of a by-passage from the inlet side of the valve to the intermediate chamber; an auxiliary valve closing the by-passage when the main valve is closed, held closed by the main valve when the latter is closed, and adapted to remain open after the latter is opened notwithstanding subsequent closure of the latter, there being means tending constantly to move the said auxiliary valve away from its seat and said auxiliary valve being arranged to constitute a latch whereby said auxiliary valve is restrained from being un-

seated by said means so long as said auxiliary valve remains closed.

7. The combination with a differential dry pipe valve having an intermediate chamber, 5 of a by-passage from the inlet side of the valve to the intermediate chamber; an auxiliary valve held closing the same when the main valve is normally closed and adapted 10 to be opened by the supply pressure when the main valve is opened; and means secured to the said auxiliary valve adapted to move it away from the by-passage and out of the path of movement of the main valve upon 15 said auxiliary valve being opened.
8. The combination with a differential valve having an intermediate chamber, of a by-passage from the inlet to the intermediate chamber; an auxiliary valve in said chamber closing said by-passage by movement in the 20 direction of closing travel of the main valve, and held closed by said main valve when the latter is closed; there being means operative when said auxiliary valve opens for moving 25 and retaining said auxiliary valve away from the by-passage in a direction transverse to the direction of closing travel of the main valve, whereby closure of the main valve following the said transverse movement of the auxiliary valve can not effect 30 closure of the by-passage.
9. The combination in a valve adapted to be held closed by air pressure exerted upon a relatively large surface area against a greater water pressure exerted upon a relatively small surface area, of an intermediate 35 chamber encircling the water passage; a

duct to said chamber from the inlet side of the valve casing; a valve for the duct, set in the chamber, held closed by the main valve when both are closed, and means set 40 in the chamber to move and hold the duct valve away from the duct when the duct valve is open.

10. A valve having an inlet passage, an outlet passage, and an intermediate chamber; a closure cutting off said chamber from said passages and closing said valve when seated; a by-passage from one of said cut off passages to said chamber; a valve in said chamber closing said by-passage and being 45 held closed by the said closure when seated; and means in said chamber operative upon the unseating of said closure for withdrawing said valve from its seat to a position where subsequent seating of the closure can 50 not effect reseating of said valve.

11. A valve having separated valve seats and a chamber intermediate thereof; a closure seating on said seats; a passage leading to said chamber from a source of pressure; 60 a valve closing said passage, held seated by the closure when seated and adapted to be opened by the pressure in said passage upon the opening of said closure; and means operative upon the opening of said valve to 65 move it to and retain it in a position beside its seat whereby the said passage will remain open notwithstanding subsequent seating of the closure.

Signed at Boston, Massachusetts, this 70 eleventh day of September, 1925.

JONATHAN C. MELOON.
